HAIR CURLER

Vernon A. Conklin, Whittier, Calif.

Application April 20, 1937, Serial No. 137,957

5 Claims. (Cl. 132—44)

This invention relates generally to the art of hair dressing, and more particularly to devices for maintaining strands of hair in curl formation.

5 An object of the invention is to provide a hair curler which is structurally characterized to enable a strand of hair to be readily wound tightly thereon, and retained in the form of a tight curl from which the curler can be easily withdrawn 10 when desired without disturbing the form of the curl, all in such manner that the curler can be worn while sleeping without discomfort to the head of the sleeper.

Another object of the invention is to provide 15 a hair curler which is entirely non-metallic and is preferably composed of a length of rubber tubing or other soft and yieldable material having similar properties, the tubing being structurally modified in an extremely simple and novel manner to form the hair curler embodying the invention.

With these and other objects in view, the invention consists in the combinations and arrangements of elements as set forth in the following specification and particularly pointed out 25 in the appended claims.

In the accompanying drawing,

Figure 1 is a view of the hair curler in side elevation;

30 Figure 2 is a view similar to Figure 1, but with the curler turned 90° therefrom;

Figure 3 is a view similar to Figure 1 and illustrating the manner in which the curler is initially manipulated in the application of a strand 35 of hair thereto;

Figure 4 is a view similar to Figure 1, but with the curler turned 180° therefrom;

Figures 5 and 6 are views showing different folded positions occupied by the curler when retaining a strand of hair in curled formation;

Figure 7 is a constricting element embodied in the curler;

Figure 8 is an enlarged transverse sectional view taken on the line 8—8 of Figure 5.

45 Referring specifically to the drawing, the hair curler embodying this invention comprises an elongated body B constructed of elastic rubber to form a tube 10 of suitable length and diameter, it being found in practice that a tube five inches 50 long and five-sixteenths of an inch in diameter is satisfactory.

One end of the tube is cut away or otherwise formed to provide a head 11 connected at one end by a neck 12 to the body portion of the tube so 55 as to provide intermediate locking shoulders

13—13. The head tapers to an approximate point at its free end so as to be substantially arrow-shaped.

The opposite end of the tube is cut away through a portion of its diameter for a short distance along the length of the tube so that for this distance the tube is laterally open. Directly opposite this open side of the tube, its wall is provided with an opening 14 through which the head 11, when contracted laterally at its widest point, 10 is adapted to be forced for co-action of the shoulders 13—13 with the walls of the opening in releasably retaining the tube folded upon itself to provide two branches a and b and a connecting bight c, as shown in Figures 5 and 6. 15

That portion of the tube providing the branch a is slit obliquely from its periphery towards the end of the tube having the head 11, and at acute angle to the longitudinal axis of the tube as indicated at 15 so as to provide a clamping tongue or 20 flap 16 which, in the bowed position of the tube shown in Figure 3, co-acts with the body portion of the tube in defining a wedge-shaped recess 17 adapted to receive a strand of hair during the 25 operation of the invention, which is as follows:

Let it be assumed that the strand of hair to be formed into a curl has been combed out as desired, and that the strand is thus ready to be applied to the tube 10. The tube is now suitably manipulated from its normal rectilinear form 30 shown in Figure 2, to assume the bowed position shown in Figure 3, following which the free end of the strand of hair is inserted into the aforestated wedge-shaped recess 17 and the tube returned to its rectilinear form for operation of the tongue 35 16 in exerting clamping pressure upon the hair strand by tending to close the recess.

With the free end of the strand of hair thus secured to the tube, the latter is rotated to wind the strand thereon, the tongue 16 functioning to 40 securely clamp the strand against displacement, and each succeeding convolution of the strand rendering the tongue more effective as will be evident from a consideration of Figure 8 which clearly illustrates that the portion of the strand 45 between the tongue and body portion of the tube is caused to be kinked and be subjected to a firm grip in order to positively prevent withdrawal of the strand, whereby to enable the strand to be tightly wound upon the tube to form a tight curl. 50

When the strand has been completely wound upon the tube along the portion thereof which is to form the branch a, the tube is folded upon itself and the head 11 forced through the opening 14 to releasably retain the tube in its folded position 55

shown in Figure 5, from which it will be noted that as a result of this folding of the tube, the tongue 16 is caused to increase its clamping pressure upon the free end of the hair strand in order to positively prevent loosening of the curl.

A constricting element in the form of an elastic rubber band or loop 18 can be applied to the folded tube over its bight c so as to more compactly hold the two branches a and b as is shown in Figure 6. When the curler is to be removed, the band 18 is first slipped from the tube and the head 11 disengaged from the opening 14 so as to permit the tube to assume its rectilinear form. The finished curl is grasped in one hand and the tube is withdrawn from the curl by pulling upon the tube in a direction axially of the curl and towards the head 11 as is intended to be indicated by its arrow shape.

By withdrawing the tube in this direction, the portion of the hair strand acted upon by the tongue 16 will shift towards the free end of the tongue and will disengage itself from beneath the tongue without disturbing the form of the curl.

25 Due to the tubular form and elasticity of the body B, the curler is comparatively soft and yieldable so that it can be worn when sleeping without discomfort to the head of the sleeper. This feature and the surety with which the hair strand is clamped to the tube 10 by the tongue 16 enable the much desired tight curls to be formed with the utmost convenience, all while affording the commercial advantages of structural simplicity and cheapness of manufacture.

3.5 What is claimed is:

40 1. A hair curler comprising an elongated flexible body having means for releasably retaining it in a position folded transversely upon itself to provide two branches adapted to support in curl formation, a strand of hair wound on one branch; and a longitudinally extending tongue on said one branch adapted to clamp the free end portion of the hair strand to the body against displacement circumferentially thereof so as to

enable the hair strand to be tightly wound upon the body to form a tight curl.

2. A hair curler comprising an elongated flexible body having means for releasably retaining it in a position folded transversely upon itself to provide two branches adapted to support in curl formation, a strand of hair wound on one branch; and means on said one branch co-acting therewith to define a wedge shaped recess extending longitudinally at an acute angle to the length of the body for the reception of the free end portion of the hair strand and the clamping thereof by said means so as to enable the strand to be tightly wound upon the body to form a tight curl.

3. A hair curler comprising an elongated flexible body having means for releasably retaining it in a position folded transversely upon itself to provide two branches adapted to support in curl formation, a strand of hair wound on one branch; said one branch being slit obliquely from its periphery at an acute angle longitudinally of the body to provide a tongue thereon for clamping the free end portion of the hair strand to the body, whereby to enable the hair strand to be tightly wound upon the body to form a tight curl. 20 23

4. A hair curler comprising an elongated body of flexible material having means to releasably retain it in a position folded transversely upon itself; the body being slit longitudinally from its periphery to provide a tongue for clamping a strand of hair when wound on the body. 30

5. A hair curler comprising a cylindrical tube of elastic rubber having a head at one end and an opening at its other end adapted to receive the head for co-action therewith in releasably retaining the tube folded transversely upon itself; the wall of the tube being slit longitudinally and at an angle to the length of the tube to provide a tongue for clamping a strand of hair wound on the body. 35 40
